UNITED STATES PATENT OFFICE

2,507,219

BABY BATH AND POWDER BOARD

Reuben W. Parker, Danville, Va.

Application April 5, 1948, Serial No. 19,061

2 Claims. (Cl. 211—86)

1

This invention relates to a baby bath and powder board for removable mounting on the rim of a bathtub.

An object of this invention is to provide a board or flat surface for mounting on the rim of a bathtub, the board having a collapsible support for holding powder or other accessories necessary to a baby bath.

Another object of this invention is to provide a board having means for supporting the same across the top of a tub, the board having a collapsible support along one edge thereof for holding powder or other accessories, and the support including an elastic band for firmly holding the articles on the support.

A further object of this invention is to provide a device of this kind which is simple in construction, light in weight, and when collapsed will occupy a small space.

With the above and other objects in view, my invention consists in the arrangement, combination and details of construction disclosed in the drawings and specification, and then more particularly pointed out in the appended claims.

In the drawings:

Figure 1 is a detail front elevation, partly broken away, of a baby bath and powder board constructed according to an embodiment of this invention.

Figure 2 is a plan view of the device.

Figure 3 is a sectional view taken on the line 3—3 of Figure 1.

Figure 4 is a fragmentary sectional view taken on the line 4—4 of Figure 2.

Figure 5 is a fragmentary sectional view taken on the line 5—5 of Figure 4.

Referring to the drawings, the numeral 10 designates generally a flat substantially rectangular board or plate which is adapted to be mounted on and supported above the rim 11 of a bathtub. The board 10 has secured to the lower side thereof a pair of elongated end bars 12 which are cut out as indicated at 13, for engagement over the rim 11 of the tub so that the end bars 12 will be held against endwise movement with respect to the rim of the tub.

A transversely extending bracing bar 14 is connected between the end bars 12 and engages under the lower side of the plate or board 10 to support and prevent warping or the like, of this board.

An article supporting member generally designated as 15 is swingably carried at the rear end of the board 10 and includes a pair of end bars 16 which are mounted on bolts 17 extending

2

through the rear portions of the side bars 12. The bolts 17 have threaded thereon wing nuts 18 so that the supporting member 15 may be secured in upright position at the rear of the board

5 10.

The side members 16 engage on the inner sides of the end members 12, and the board 10 is cut out at its opposite rear corners, as indicated at 19, so that the small portion of the board 10 will be disposed beneath the supporting member 15. The supporting member 15 has secured to the forward edges of the bars 16 a plate or board 20, and a shelf strip 21 is secured to the board 20 at a point between the upper and lower edges 15 thereof.

The shelf 21 is formed of an elongated narrow strip which is provided at its upper side with a longitudinal groove or channel 22. An elongated flexible and relatively elastic band or strip

20 23 is secured at the opposite ends thereof to a pair of end blocks 24 which are secured to the forward side of the board 20 above the bottom or shelf member 21. The flexible member 23 is secured as at 25 to the forward side of the board 20 at a point medially between the ends of this board, as shown in Figure 2.

In the use and operation of this device, the cut-outs 13 in the opposite ends, and the lower edges of the end members 12 are spaced apart a distance sufficient to provide for extension of a portion of the end members 12 inside the rim 11 of the tub so that while the device may be shifted lengthwise of the tub, the device cannot be moved laterally or crosswise with respect to the tub.

The article supporting member 15 when in operative position is disposed in vertical upwardly extending position as shown in Figure 3. The various articles forming accessories to the bath 40 and other operations may be placed on the supporting member 15 inside the elastic band 13.

When the supporting member is collapsed, the wing nuts 18 are loosened and this device is then swung downwardly and inwardly so as to engage beneath the board 10 and between the end members 12. This device will, when in collapsed position, occupy only a relatively small space and when in applied position will provide a firm 45 foundation which can be mounted on the rim of the tub.

I do not mean to confine myself to the exact details of construction herein disclosed, but claim all variations falling within the purview of the 50 appended claims.

What I claim is:

1. A bath and powder board for removable mounting on the rim of a bath tub comprising a rectangular plate, a pair of bars secured to the under side of said plate and projecting beyond the front and rear edges, said bars being formed with cut-outs in the lower edges thereof adjacent each end for receiving the rim of the bathtub, an article supporting rack, and means swingably supporting said rack for movement from a collapsed position beneath said plate to an upright operative position extending above said plate.

2. A bath and powder board for removable mounting on the rim of a bathtub comprising a rectangular plate, a pair of bars secured to the under side of said plate and projecting beyond the front and rear edges, said bars being formed with cut-outs in the lower edges thereof adjacent each end for receiving the rim of the bathtub, an article supporting rack swingably carried by the rear portions of said bars, said rack including an elongated board, a pair of bars fixed to the opposite ends of said board, means pivotally

securing said latter bars to said first named bars, end members secured to the forward side of said board, a bottom forming strip secured between said end members, an elastic strap fixed between said end members, and means securing the medial portion of said strap to said board.

REUBEN W. PARKER.
